UNITED STATES PATENT OFFICE.

CLAUDE E. COX, OF DETROIT, MICHIGAN.

AUTOMATIC OIL-CUP.

1,382,823.

Specification of Letters Patent. Patented June 28, 1921.

Application filed January 29, 1921. Serial No. 441,026.

To all whom it may concern:

Be it known that I, CLAUDE E. Cox, a citizen of the United States, residing at Detroit, in the county of Wayne and State of Michigan, have invented certain new and useful Improvements in Automatic Oil-Cups, of which the following is a specification.

My invention relates to improvements in oil cups, and more particularly to oil cups of the type disclosed in my prior Patent No. 1,357,616 dated November 2, 1920, wherein the oil receptacle has an upright hollow post therein inclosed by a sleeve freely slidable 10 on the post and normally maintained in elevated position by a spring so that vibration of the structure may cause the spring-sustained sleeve to ride up and down, feeding oil into the open end of the post.

General objects of my present invention are to improve the feeding action of the device while maintaining simplicity and economy in construction and to effect a novel and advantageous coördination of the post 20 and sleeve.

In the drawing wherein I have illustrated an embodiment of my invention Figure 1 is a vertical section of an oil cup constructed in accordance with my invention and Fig. 2 30 is a horizontal section on line 2—2 of Fig. 1.

The cylindrical oil cup 10 has in its externally threaded throat 11 a tapered recess 12 in which is drive fitted the conical base 13 of the upright post 14 whose axial duct 35 15 forms the oil outlet. The tip of the post, internally beveled to provide the sharp edge portion 16, preferably extends well into the upper portion of the oil chamber 17 so as to stand above any working liquid level of 40 the oil, a medium oil level being indicated by dotted line. Any suitable cover 18 may be provided in conjunction with the body receptacle, that construction of cover specifically shown being not herein claimed, but 45 conveniently providing a movable top plate 19 to expose or cover the filling orifices 20.

The sleeve 21 surrounding the stem or post 14 is of length to extend from near the bottom of the latter to above its top, is provided 50 at its top with a flange 22 that also constitutes a weight normally standing above the oil level, and is normally held in raised position by a light spring 23 loosely encircling the sleeve and extending from the bottom 55 of the casing to the under side of the flange 22.

Save in refinements, the structure thus far described is generically that of my prior patent, but by special construction and co-operation of the sleeve and post or stem I 60 increase the available feed-rate and the certainty and regularity of the feed. As in my prior construction, vibration of the oil cup structure results in a limited vertical displacement of the sleeve, causing that portion 65 of the sleeve which is contiguous to the open mouth of the stem or post to ride up and down past the edge 16 and so causing oil, entrained between the contiguous surfaces of the generally-coaxial sleeve and stem to 70 be fed into the hollow interior or duct 15 of the stem. In the improved construction herein shown, however, I so relatively construct the contiguous surfaces of the sleeve and stem that the forces expressed on the 75 downward movement of the sleeve involve a component tending to cause the top of the stem to disrupt or cut through any oil film on the sleeve thereby to prevent, with certainty, the sleeve from idly carrying up and 80 down a film of oil without feeding it into the duct of the stem or post. And further, I so construct these parts that the relative action between the stem and sleeve involves a pumping effect tending to force oil entrained 85 between the surfaces to the top of the sleeve.

And further, I so construct that the film-breaking or disrupting action above referred to is supplemented by a similar action at a lower point on the stem or post. And further I provide for particularly efficient and lightly-responsive vibratory action of the sleeve.

In the specific construction shown portions of the confronting surfaces of the post 95 and sleeve are relatively tapered, the sleeve 21 being shown as having a bore 25 uniformly tapered, although but very gradually, from bottom to top, its top being barely larger than the top diameter of the post to 100 work as close to the latter as is feasible without binding. At a lower point, as by a shoulder 26 on the stem, the sleeve is guided to maintain approximately its coaxial relation with the stem, and it will be apparent that 105 in its vertical reciprocation the inertia forces which act to drive the sleeve down are resolved into two components one of which is normal to the surface of the tapered hole or bore and tends to result in the sharp edge 16 of the post or stem cutting through 110 the film of oil between the sleeve and post.

Thus it is insured that oil upon the upper portion of the surface of the sleeve will be scraped off, to flow through the outlet duct 15 of the stem.

5 Further, the post coacting with the taper-bored sleeve is preferably formed in two cylindrical reaches or steps with the shoulder 26 intervening, this shoulder being preferably well toward the bottom of the stem 10 so that there is left a long gradually tapering oil space 29 above the shoulder 26 and around the upper cylinder portion 27. In addition to its guidance function above referred to the shoulder 26 forms a cut-off edge 15 that tends to break the oil film for reasons above explained and the oil space 29, variable in area as the taper-bored sleeve rises and falls, has oil trapped therein and subjected to varying pressures as the available 20 area therefor increases and decreases, so that the inevitable pumping action results in a material flow of the oil under pressure upward toward the top of the post 14.

Remembering that the effected dimensions 25 are all rather minute, and that, as indicated in my prior patent, capillation alone, supplemented with the mechanical vibration of the sleeve, suffices for a substantial and in many instances sufficient feed, it will be apparent that the certitude of oil film breaking, of redistribution of the oil along the 30 surfaces and of sensitiveness that results from the diminution of the areas of close contiguity of the post and sleeve surfaces 35 are factors that coöperate to improve the functioning of the device.

While I have herein described in some detail a particular embodiment of my invention for purposes of full disclosure of a 40 practical and operative device, it will be apparent to those skilled in the art that changes in detail may be made within the

teachings of my invention and within the scope of the appended claims.

I claim:

1. In an oil cup comprising a receptacle, a hollow post upright therein and a sleeve slidably mounted on said post to rise and fall under the effect of vibration, a coöperative construction of the sleeve and post that 50 regulates their confronting surfaces adjacent the top of the post at an oblique angle.

2. In an oil cup of the character described, generally coaxial post and sleeve members, the latter normally extending above the top of the former, the inner surface of the upper portion of the sleeve being disposed at an oblique angle to the outer surface of the 55 upper portion of the post.

3. In an oil cup of the character described, a post having a cylindrical top portion and an oil feeding sleeve surrounding the post and normally extending above the top thereof, said sleeve having an upwardly tapering bore.

4. In an oil cup of the character described, the combination of a post having external cylinder formed zones of different diameters and an internally tapering sleeve.

5. In an oil cup of the character described, a post having a relatively short bottom portion, a shoulder 26, a relatively long cylindrical upper portion terminating in a sharp edge 16, and an enveloping sleeve having a tapered bore that normally extends below 75 the shoulder 26 and above the edge 16.

6. In an oil cup of the character described, a relatively stationary post member and a relatively vibratable sleeve member, these shaped as to their confronting surfaces to 80 present an oil space therebetween that is variable in area as the sleeve is vibrated relatively to the post.

CLAUDE E. COX.
